LADY'S STOCKING

John K. Voehringer, Jr., Greensboro, N. C., assignor to Mojud Hosiery Co., Inc., Long Island City, N. Y., a corporation of Delaware

Application August 14, 1951, Serial No. 16,264

Term of patent 14 years

(Cl. D47—7)

To all whom it may concern:

Be it known that I, John K. Voehringer, Jr., a citizen of the United States and a resident of Greensboro, county of Guilford, State of North Carolina, have invented a new, original, and ornamental Design for a Lady's Stocking, of which the following is a specification, reference being had to the accompanying drawing forming part thereof.

In the drawing—

The stocking is characterized by the inclusion of a diamond mesh heel splice, carrying a closer knit mesh band below the heel, that band substantially matching in texture the balance of the foot, and a further narrow border of the same texture extending around the heel and merging into the band.

I claim:

The ornamental design for a lady's stocking, as shown and described.

JOHN K. VOEHRINGER, JR.
